WIRE UNREELING APPARATUS

Claude L. Metzler, Berea, Ohio, assignor to The American Steel and Wire Company of New Jersey, a corporation of New Jersey

Application August 27, 1947, Serial No. 770,831

6 Claims. (Cl. 242—78)

1

This invention relates to apparatus for unreeling wire from spools or coils, and particularly for continuously unreeling wire from non-revolving spools or coils.

The apparatus of the present invention is especially suited for paying off wire to wire drawing dies in continuous wire drawing operations, wherein the trailing end of the wire on each spool is butt welded to the leading end of the wire on the next spool, and thus a continuous length of wire passes through the dies. However, it is obvious that use of the apparatus is not limited to this or any other specific application, but may involve any application where it is desired to unreel wire continuously.

An object of the invention is to provide improved apparatus for successively feeding spools or coils of wire to a pay-off position where the wire is unreeled, while maintaining the spool or coil stationary.

A further object of the invention is to provide improved apparatus for continuously paying-off wire wherein the leading and trailing ends of successive coils may be joined preliminary to feeding of the coil, and such joining does not interfere with paying off of the wire.

A further object of the invention is to provide improved wire unreeling apparatus wherein actuation of stops discharges an exhausted spool from pay-off position and moves a full spool thereto by gravity, the change-over not interfering with continuous paying off of the wire.

In accomplishing these and other objects of the present invention, I have provided improved details of structure, a preferred form of which is shown in the accompanying drawing, wherein:

Figure 1 is a vertical sectional view through an unreeling apparatus embodying features of the present invention;

Figure 2 is a top plan view of a portion of the apparatus; and

Figure 3 is a sectional view on line III—III of Figure 1.

Referring more in detail to the drawing:

The apparatus of the present invention comprises a box-like chute 10 of rectangular cross-section and preferably of sheet or structural steel. The chute is supported in a downwardly inclined position by any suitable supporting elements, as, for example, side plates or legs 11, as shown in Figure 1. Preferably angle iron cross braces 12 span the underside of the chute floor to furnish rigidity. The ends of chute 10 are open for insertion and discharge of spools of wire.

In Figure 1 there is shown a spool of wire 13 in

5 pay-off position and a second spool 14 ready to be shifted to pay-off position when the wire from spool 13 is exhausted. The leading end of the wire of spool 14 is welded to the trailing end of the wire of spool 13, as indicated at 15. Thus, when spool 13 is exhausted, paying off of wire may continue from spool 14.

The spools are retained in the positions shown by retractable stops 16 and 17 that project through the chute floor and engage said spools. The details of the stop mechanism are shown in Figure 3, which shows stop 16, it being understood that stop 17 is of similar construction.

Stop 16 includes pins 18 and 19 which are pivoted to the adjacent cross brace 12. Said pins project through slots 22 and 23 in the chute floor, and in their extended position they engage the spools as shown in Figure 1 to prevent the spool's sliding down the chute. A U-shaped operating handle 24 is pivoted to said pins. Movement of said handle to the right, as viewed in Figure 3, retracts the pins, whereby the spool is free to slide down the chute.

A preferred form of mechanism for guiding wire paid off from a stationary coil is shown in detail in Figures 1 and 2. The chute top has a circular opening 25 of somewhat larger size than a spool and being coaxial with spool 13 in pay-off position. Said opening is surrounded by a guide flange 26 of circular outline. A cross arm 27, having rollers 28 riding on the inside of said flange, extends across the diameter of the opening and is adapted to revolve about the spool axis. One end of said arm carries a tubular spindle 29, to which a sheave bearing 30 is pivoted to turn about an axis parallel to the axis of rotation of the arm. A sheave wheel 31 is rotatively carried by said sheave bearing to turn about an axis normal to the axis of rotation of the bearing. The bore of spindle 29 is tangential to the circumference of sheave 31.

It is to be noted that wire is commonly reeled on spools in such fashion that both the leading and trailing ends of a full spool are accessible externally to permit welding to both end.

The operation of an improved unreeling apparatus constructed as described is as follows:

The leading end of wire on a spool is fed around sheave 31 and through the bore of spindle 29 to the wire drawing dies or other mechanism in which the wire is to be used. The trailing end of the wire on this spool is welded to the leading end of wire on another spool.

The first spool is introduced to the chute from the upper end, from which it slides by gravity to

stationary pay-off position 13. The second spool is similarly introduced to the chute and occupies upper position 14. The spools are retained in these positions by stops 16 and 17 respectively, which are extended.

Wire is paid off from spool 13 by a force applied to the wire externally of the apparatus. Pull on the wire turns arm 27 about the spool axis and carries the wire from the spool. At the same time sheave bearing 30 and sheave 31 turn about their respective axes so that said sheave is always directed toward the spool and guides the wire through the spindle bore.

In the meantime the trailing end of the wire on spool 14 is welded to the leading end of the wire on a third spool.

When the wire on spool 13 is exhausted, stops 16 and 17 are retracted by the mechanism shown. The spool 13 slides through the open lower end of the chute by gravity and is discharged and spool 14 slides to pay-off position, where it is retained by again extending stop 16. The third spool is introduced to upper position in the chute.

Thus it is seen that with the improved apparatus of the present invention spools may be moved to pay-off position continually with no interruption of unreeling. By maintaining the spools stationary during paying off of the wire, the danger of snarls is eliminated and the trailing ends are free for welding.

While I have described only a single embodiment of the invention, it is apparent that modifications may arise without departing from the spirit of the invention. Therefore, I do not wish to be limited by the disclosure set forth, but only by the scope of the appended claims.

I claim:

1. Wire unreeling apparatus comprising a downwardly inclined chute, retractable stop means for retaining a spool of wire in said chute in a pay-off position, retractable stop means for retaining a second spool in a position above pay-off position from which it may be shifted to pay-off position, and means for guiding wire unreeled from the spool in pay-off position.

2. Wire unreeling apparatus comprising a chute having open ends, stop means projecting into said chute for retaining a spool of wire in a pay-off position, additional stop means projecting into said chute for retaining a second spool in a position from which it may be shifted to pay-off position, and means for guiding wire unreeled from the spool in pay-off position.

3. Wire unreeling apparatus comprising a downwardly inclined chute having open ends,

retractable stop means projecting into said chute for retaining a spool of wire in a pay-off position, additional retractable stop means for retaining a second spool in a position above pay-off position from which it may be shifted to pay-off position, and means for guiding wire unreeled from the spool in pay-off position.

4. Wire unreeling apparatus comprising a downwardly inclined chute having open ends, retractable stop means projecting into said chute for retaining a spool of wire in a pay-off position, additional retractable stop means for retaining a second spool in a position above pay-off position from which it may be shifted by gravity to pay-off position on retraction of said additional stop means, the spool in pay-off position being discharged from the chute on retraction of said first-named stop means, and means for guiding wire unreeled from the spool in pay-off position.

5. Wire unreeling apparatus comprising a downwardly inclined chute having open ends, retractable stop means projecting into said chute for retaining a spool of wire in a stationary pay-off position, additional retractable stop means for retaining a second spool of wire in a position above pay-off position from which it may be shifted to pay-off position, and rotatable means for guiding wire unreeled from the spool in pay-off position.

6. Wire unreeling apparatus comprising a downwardly inclined chute having open ends, retractable stop means projecting into said chute for retaining a spool of wire in a stationary pay-off position, additional retractable stop means for retaining a second spool in a position above pay-off position from which it may be shifted by gravity to pay-off position on retraction of said additional stop means, the spool in pay-off position being discharged from the chute on retraction of said first-named stop means, and rotatable means for guiding wire unreeled from the spool in pay-off position.
